AUTOMATIC LOCK FOR HOISTING
MECHANISMS

Henry A. Geerds, Holland, Mich., assignor to
Holland Hitch Company, Holland, Mich., a corporation of Michigan

Application April 4, 1949, Serial No. 85,444

12 Claims. (Cl. 192—8)

1

This invention is directed to an automatic lock-
ing or holding means for hoisting mechanisms.

The hoisting jacks are used, in one place of use thereof, in connection with trailers which are detachably connected with trucks. Such hoisting jacks ordinarily mounted at the under side of and adjacent the front end of said trailers, being retracted when the trailer is connected to the truck which pulls it, and extended when a destination is reached and the truck is disconnected from the trailer, the hoisting jack supporting the trailer at a proper level and with the bottom of the body of the trailer generally horizontal, the trailer having no other means of support at its front end.

A hoisting jack of the type noted has been provided with a shaft having a continuous worm thread at its outer side passing through an interiorly threaded sleeve to receive it, the worm being mounted upon one section of the extensible hoist and the sleeve on another section thereof, the two sections of the hoist being telescoped one within the other. Turning the worm shaft may either extend or retract the hoist depending upon the direction of turning. When the shaft has an outwardly projecting helical thread fitting into the interior threads of the sleeve, the sleeve and shaft will remain in any position to which adjusted, in effect providing a lock against accidental or other undesired change of position of the relatively extensible parts of the hoist. At the same time the shaft may be turned for such extension or retraction when wanted. But the force which has to be exerted may be heavy, particularly in lifting a loaded trailer at its front end above its connection to a tractor which pulls it.

For the purpose of decreasing the force which may be used for operating the hoist there has come into use helically grooved shafts and sleeves in both of which continuous helical grooves are cut and with balls seated in cooperating grooves in the interiorly grooved sleeve and the exteriorly grooved shaft which greatly reduces friction in turning the shaft. Such construction however does not retain the locking qualities of the previous worm thread connection of the shaft and sleeve so that it has become necessary to provide an accessory lock which will insure that the hoist parts do not change position relative to each other either when the trailer is being pulled over the road or when it is standing at a depot with the hoist supporting the trailer and its load at its front end.

It is an object and purpose of the present in-

2

vention to provide a very effective and practical lock of the type mentioned which is releasable on manual turning the helically grooved shaft in either direction so as to permit extension or retraction of the hoist parts, but which will securely retain the hoist in any positions to which have a plurality of it may be operated. It is a further object and purpose of the invention to provide a lock which is of economical structure, sturdy and durable in service and which is readily and easily installed.

An understanding of the invention may be had from the following description, taken in connection with the accompanying drawings, in which,

15 Fig. 1 is an elevation, partly in longitudinal vertical section, of one of the hoist members which may be used with a trailer or other like conveyance and showing the lock which I have invented applied thereto in elevation.

20 Fig. 2 is a horizontal section through the hoist lock substantially on the plane of line 2—2 of Fig. 3, the plane of the section being substantially midway between the inner and outer sides of the lock housing.

25 Fig. 3 is a vertical section substantially on the plane of line 3—3 of Fig. 2, showing the inner mechanism of the lock in elevation.

30 Fig. 4 is a fragmentary partial section and end elevation, similar to Fig. 3, showing the locking mechanism in a different position and indicating one direction of turning of the hand crank which operates it.

Fig. 5 is a view similar to Fig. 4 with the crank turned in the opposite direction.

35 Fig. 6 is a view similar to Fig. 5 showing the mechanism after said crank has been turned in the opposite direction a greater distance.

40 Fig. 7 is a view similar to Fig. 6 of a modified and preferred form of construction, including a brake operable in one direction and held from operation in the other.

Fig. 8 is a plan view of the braking element, with parts in section illustrating the manner of release thereof.

45 Fig. 9 is a fragmentary section through the housing and the associated brake, at one side of the housing, and,

Fig. 10 is a perspective view of the braking element.

50 Like reference characters refer to like parts in the different figures of the drawings.

The extensible and retractable hoist mechanism, two of which are normally used in the large trailers drawn by trucks in freight transportation, each has, at its lower end, spaced wheels

55

mounted in connection with a suitable axle housing 2, between which wheels a vertical and generally hollow tubular member 4 permanently connected at its upper end to a gear housing casting 5 associated one with each of the chassis frame members of the trailer body. An exterior helically grooved shaft 6 at its upper end portion passes through the bottom of the gear housing 5 and is rotatably mounted therein and at its lower grooved portion passes through an interiorly grooved sleeve 7 permanently secured at the upper end portion of the post 3. Balls 8 fill the complementary grooves of the shaft 6 and sleeve 7 for the length of said sleeve. When the shaft 6 is rotated the sleeve 7 moves along said shaft 6 in the direction of its length moving upwardly in one direction of the turning of said shaft and downwardly in the other. The details of the movement of the balls 8 and how they are controlled need not be entered into as such structure is old and well known.

At the upper end of the shaft 6 a beveled pinion 9 is keyed or otherwise fixedly secured, which meshes with a second beveled pinion 10 keyed to a horizontal shaft 11 which passes through a suitable bearing for it in a side of the gear housing 5 and adjacent chassis side frame member. A universal joint 12 connects said shaft 11, which is of short length, at its inner end with an equalizing shaft 13 which extends to a like hoisting unit associated with the other side chassis frame member of the trailer body, whereby a rotation of shaft 11 raises or lowers the telescoping posts 3 and wheels 1 associated therewith simultaneously and in equal amounts.

With the previously mentioned worm shaft and sleeve used in which no additional lock is required, said shaft 11 would continue through the housing and be rotatably mounted adjacent its outer end in a second bearing in the opposite side of the housing 5, and at its outer free end portion be equipped with a crank to turn the shaft. With my invention the shaft 11 extends nearly to but terminates short of the opposite vertical side of the housing 5. The locking mechanism of my invention is mounted at the outer vertical side of said opposite side of the housing. Said locking mechanism includes a generally box structure having a vertical plate 14 at its inner side, from which a square surrounding enclosure having sides 15 extending outwardly are cast integrally with the plate 14. The outer open side of this box is covered by a second vertical plate 16, the plates 14 and 16 having outwardly extending ears, as indicated by the ears 14a on the plate 14 (Fig. 3), between which ears sleeve collars 17 are located. Headed screws 18 pass through openings in the plate 16 and said ears into interiorly threaded openings bored to receive their inner ends in the gear housing 5 (Fig. 1). Each of the sides 15 of the box, substantially at its middle is provided with an inner generally semi-circular groove or recess 19, each having the same radius of curvature as the inner corners at the meeting ends of the sides 15 of the box and are of rounded form as shown.

A circular plate 20 is located in the box against the inner plate 14 and may freely turn about a horizontal axis. The plate has a central opening through it and a hollow sleeve hub 21 extends therefrom through the plate 14 and through a bearing in the adjacent side of the gear housing 5. The adjacent end of the shaft 11 is reduced in diameter to enter the sleeve 21 (Fig. 2), a bolt passing through the sleeve and the end of the

shaft 11 to securely connect said sleeve and shaft together. From the plate two spaced pins 22 extend outwardly, both being located to one side of a diameter of the plate (Fig. 3).

Against the circular plate 22 a floating locking member 23 is positioned, of irregular shape as best shown in Fig. 3, and which at one end is equipped with a roller 24 mounted on an outwardly extending pin, the roller having a radius 10 of curvature corresponding to the radius of curvature of the recesses 19 and of the inner corners of the box described. At the opposite end of the floating member 23, which is made from a flat plate of metal, an idle grooved roller 25 is mounted on a supporting pin which extends outwardly from the member 23. A coiled tension spring 26 has its ends connected with the pins 22 and rides between its ends in the groove of the roller 25. Said floating member 23, at opposite sides 20 between the rollers 24 and 25, has oppositely projecting fingers 27 which at their inner edges in conjunction with the edges of the plate 23 provide recesses into which the pins 22 may be received. The floating member 23 also has two spaced pins 28 extending outwardly therefrom, of a smaller diameter than the pins 22, one at each side of a somewhat elongated slot 29 formed through the locking member 23, having its longitudinal axis substantially coincident with a line joining the axes of the pins on which the rollers 24 and 25 are mounted.

The outer closure plate 16 of the box which houses the locking mechanism has a central hub through which a short shaft 30 rotatably passes. 35 Such shaft, at its inner end portion, passes through the slot 29 and has a reduced inner end which is rotatably received in the sleeve 21 of the plate 20. A relatively heavy and short rod 32 is connected with the shaft 30, extending radially therefrom, and lies at the outer side of the locking member 23. It is of a length that when the shaft 30 is manually operated by the crank 31 secured at its outer end, the rod 32 comes against pins 22 and 28, those at the right of the shaft 30 (Fig. 3) in one direction of turning movement, and those at the other side of said shaft 30 in the opposite direction of movement. The roller 24 may be in any corner of the box housing, being shown in one corner thereof in Fig. 3, or it may be in any one of the recesses 19 at the conclusion of a crank rotation of the shaft 30 in either direction.

With the movable locking plate in a position such that the roller 24 thereon is seated in one of the eight seats therefor at the inner side of the lock housing, spring 26 acting on the plate moves it so that roller 24 will enter such seat as it comes to it. On turning the crank 31 so as to rotate the short shaft 30 in a clockwise direction (Figs. 3 and 4), the radially extending rod 32 first strikes a pin 22 on the plate 20 and continues in contact therewith until and after it engages the adjacent pin 28 on the floating locking plate 23 after which two members 20 and 23 turn in unison. The roller 24 (Fig. 4) follows the inner side of the adjacent sides 15 of the lock housing with a movement of the locking plate 23 such that the slot 29 is progressively changed in position with relation to the shaft 30 until a recess 19 is reached whereupon the roller 24 enters such recess; and if the extension of the hoist is as much as wanted, will remain in such recess on cessation of the operation of the crank 31. However, the operation of the crank 31 may be continued and the two members 20 and 23 turned

as far as wanted and through any number of complete revolutions until the necessary extension of the hoist has been obtained. The roller 24 will be seated in either one of the corners of the lock housing or in one of the recesses 19.

As is apparent, shaft 6 is locked against uncontrolled rotation in either direction under influence of either the weight of posts 3 or the load supported thereon, by the interposition of roller 24 in a recess 19 at an arc greater than the arc of travel of pin 22. Hence on shifting of load direction, the rotation of shaft 6 is limited to the distance provided for the transfer of contact between the opposite finger 27 and pin 22. The tension of spring 26 maintains the roller 24 in its recess during the transfer period.

To reverse the operation, the crank 31 is turned in the opposite direction which causes the shaft 30 to move counter-clockwise (Figs. 5 and 6), the opposite pin 28 being first engaged by the radially extending rod 32 followed shortly after by engaging the other pin 22. While the locking plate 23 may have a limited rocking movement with respect to the plate 20 against which it is located, it is only that which is permitted by the position of the fingers 27 and the pin receiving recess between such fingers and the plate 23 of which they are an integral part. Thus if a rotation of the crank 31 should be stopped with the roller in the position shown in Fig. 4 the force of spring 26 would cause the locking plate 23 to be turned counter-clockwise so as to seat in the adjacent corner recess, while if the roller 24 was at the opposite side of the intermediate recess 19 the plate 23 would be rocked by the spring 26 to move the roller to the adjacent corner seat for it. Of course if the roller 24 is in a recess 19, as in Fig. 6, the locking dog will remain fixed and any change of position of the shaft 6 will be only until a pin 22 is in a recess at one of the fingers 27.

In Figs. 7 to 10 inclusive, the surrounding enclosure 15 of the previously described structure, is made of circular form as at 15a, and the semi-circular recesses 19 at the inner side thereof are greatly increased in number as at 19a (Fig. 7) and are in close succession one after the other. The circular plate 20a in place of the previously described plate 20, at one side has a radially disposed slot 33 from the edge thereof inwardly for a distance, and at the slot at one side the plate has an outward projection as shown in Fig. 7.

A braking element of a strong wire or wire rod, or an equivalent, has an end portion formed as a generally radially disposed finger 34 which enters the slot 33. The braking element is of an approximately circular form, as indicated at 35, and normally springs outward to seat in a V-shaped groove therefor at the inner side of the enclosure 15a between the inner ends of the recesses 19a and the bottom 14 of the enclosure. Such braking element extends around the inner side of said enclosure until it reaches a point spaced a short distance from the finger 34, whereupon it is bent inwardly and extends from the bend a short distance, and terminates in a finger 36 at right angles to the plane of finger 34, extending toward the open side of the enclosure 15a which in practice, upon installation, will be closed by a closure plate like the plate 16 in Fig. 1.

The floating locking member 23 with the roller 24 thereon, the oppositely disposed roller 25 and the tension spring 26 partly around the latter roller and connected with the pins 22 on plate

20a are substantially the same, roller 24 being adapted to successively seat in the recesses 19a. The pin 32 on the shaft 30, previously described, is replaced by a differently shaped projection 32a, serving the same purpose.

From the shaft 30 an arm 37 extends radially outward reaching nearly to the inner side of the enclosure 15a, and having a free end which, in the movement of the arm in one direction, comes against the finger 36 of the brake element. By pressing thereagainst, the generally circular braking element 35 is contracted and in a great measure pulled away from the groove in the inner side of the wall of the enclosure 15a. Therefore, on a rotation of the shaft 30 in a counter-clockwise direction, with reference to Fig. 7, the structure described operates identically with, and has the same freedom of movement as, that of the first described structure, except there is a greater succession of seatings of the roller 24 in the greater number of recesses 19a which receive it.

In the opposite direction, or the clockwise movement of the shaft 30 with reference to Fig. 7, the arm 37 moves away from the finger 36, releasing the brake so that it transmits its full retarding or braking effect against the wall of the enclosure 15a and thereby checks abrupt jars or shocks as the roller 24 moves from one recess 19a to the next succeeding recess. Such jars otherwise take place and, under certain load conditions of a trailer, may take place to a degree with the first described structure that is undesirable. Therefore, the structure illustrated in Figs. 7 to 10 inclusive is a preferred structure, having the same ease of operation in one direction of turning of the shaft 30 by the crank 31 connected to it (Fig. 1), while in the other direction the weight of the load will serve to overcome what might be a heavy expenditure of effort required by the operator to manually turn the shaft 30 if there were no load. But the operator is not required to expend excess energy in attempting to soften jars or shocks occurring as the load is lowered, because the braking serves to soften and check and substantially eliminate such jars or shocks coming therefrom as the roller 24 moves from one recess 19a to another next adjacent.

With the construction described the ease of operation of the hoist provided by the ball and groove mechanism of the shaft 6, sleeve 7 and balls 8 is retained and the hoist in the position to which it is extended or retracted maintaining such position. The structure is novel, economical to produce, easily installed and has a long life of service. It has proven very practical and effective for the purposes for which it has been produced.

The invention is defined in the appended claims and is to be considered comprehensive of all forms of structure coming within their scope.

I claim:

1. In a structure as described, a box-like housing having a bottom and outer closure with sides at an angle to each other, each of said sides having a recess therein and each of the corners at the juncture of sides of the box having a similar recess, a plate located within the housing adapted to be connected to a shaft which is to be releasably held in a position to which turned, two spaced pins secured to and extending from said plate, a floating plate member located against a side of the first plate having means at one end adapted to seat in any of said recesses, said floating member, between its ends, having a longitudinal slot closed at both ends, two

spaced pins extending from said floating member, a resilient elastic member extending between the pins on said first plate, means projecting from said floating member adjacent its opposite end, said yielding resilient means bearing against the outer sides thereof, to normally move the floating member in a direction to move its recess engaging means toward the sides of said housing, a short shaft extending into said housing through the outer closure thereof, and a rod connected to said shaft and extending radially therefrom adjacent said floating member, having a length so as to engage against all of said pins, and means for manually turning the shaft.

2. A structure as defined in claim 1, said first plate having a hollow hub at its middle portion extending through and rotatably mounted on the bottom of the housing, said hub being permanently secured to the first mentioned shaft, and said short shaft having a reduced inner end portion rotatably mounted in the inner end of said hub.

3. A structure as defined in claim 1, said first plate being of circular form and the pins carried thereby being spaced from each other an arc distance of less than 180°, and said pins on the floating member being spaced from each other an arc distance of substantially 180°.

4. A structure as defined in claim 1, and two fingers located one at each side of said floating member, forming with the adjacent edges of said floating member, open hooks providing recesses in which said first mentioned pins on said first plate are adapted to be received.

5. A device of the class described comprising, a box-like housing of substantially square form having an inner bottom, side walls at right angles to said bottom and an outer closure over the outer side of the housing, said walls each having an arcuate recess therein at its inner side, and each of the inner corners of the housing being of an arc-shape having substantially the same radius or curvature as the recesses, a circular plate located against the inner side of the bottom of the housing having a hollow sleeve hub extending through said bottom, a shaft extending through the closure of said housing and rotatably mounted therein having an inner reduced end rotatably entering said hub, a floating member comprising a flat member of metal located against the outer side of said plate, said floating member having a slot with closed ends through which the shaft passes, a roller at one end of the floating member adapted to enter any of said recesses in the sides of the housing to which brought or seat in the corners thereof, yielding spring means between said plate and floating member pressing said roller outwardly to engage the inner sides of the housing, and means projecting from said plate and said floating member combined with means carried by said shaft to engage therewith on rotation of the shaft for turning said plate and for turning and longitudinally moving said floating member.

6. A structure as defined in claim 5, said means on the plate and on said floating member comprising two spaced apart pins secured to the plate and extending outwardly therefrom and two additional pins spaced from each other fixed to said floating member and extending outwardly therefrom between its ends and disposed nearer the axis of said shaft than the pins on said plate, and said means on the shaft comprising a radial arm secured to said shaft and lying over the outer side of said floating member, said pins being

located in the path of movement of said arm on rotation of the shaft.

7. A structure as defined in claim 6, and two fingers, one at each side of said floating member, located between opposite ends thereof, said fingers forming with the floating member open hooks into which the pins on said plate are adapted to be received.

8. In a structure as described, a box-like housing having a bottom and outer closure and side wall between, said side wall having recesses at the inner sides thereof, a plate located within the housing adapted to be connected to a shaft which is to be releasably held in a position to which turned, a floating plate member located against a side of the first plate having means at one end adapted to seat in any of said recesses, said floating member between its ends having a longitudinal slot, yielding means moving said floating member in a direction to seat said means at its end in a recess when opposite it, a short shaft extending into said housing and through said slot in the floating member, and cooperating means on the shaft and said first plate for turning said first plate by said shaft, substantially as described.

9. A structure as defined in claim 8, and a resilient brake member connected at one end with said first plate and normally pressing against the inner sides of said housing wall, being movable with said first plate on movement thereof to frictionally resist such movement in one direction, and a member connected to said short shaft and movable therewith engageable with said brake member on rotation of the short shaft in the opposite direction, to contract the brake member and permit free rotative movement of said first plate.

10. In a structure as described, a box-like housing having a bottom and outer closure with side walls between them, said walls having a plurality of recesses therein at the inner side, a generally circular plate located within the housing adapted to be connected to a shaft which is to be releasably held in a position to which turned, two spaced pins secured to and extending from the plate, a floating plate member located against a side of the first plate, having means at one end adapted to seat in any of said recesses, said floating member between its ends having a longitudinal slot closed at both ends, two spaced projections extending from said floating member at opposite sides of said slot, a resilient elastic member extending between the pins of the first plate, means projecting from said floating member adjacent its opposite end bearing against said resilient means between its ends, for normally moving the floating member in a direction to seat said recess engaging means in any recess to which it comes, a short shaft extending into said housing through the outer closure, a member connecting to said shaft extending radially therefrom adjacent said floating member having a length so that all of said pins are in its path of movement, and means for manually turning said short shaft.

11. A structure as defined in claim 10, said generally circular plate having an inwardly extending slot at one side, a generally circular brake member bearing against the inner sides of said wall of the housing near the bottom thereof having an end extending into said slot and having its other end spaced from said first mentioned end of the brake member terminating in a section generally paralleling the adjacent wall, and an

arm connected to said short shaft and movable therewith in the path of movement of the outer end of which said terminal section of the brake member is located.

12. A structure as defined in claim 11, said brake member consisting of a resilient length of metal having the end thereof connected with said plate in the slot thereof located generally radially with respect to said brake member, and said wall of the housing having a continuous V-shaped groove therein in which said brake member is seated and against which it normally bears with resilient pressure, the other end of the metal

brake member which is located generally parallel to the adjacent wall being disposed slightly inwardly from the wall.

HENRY A. GEERDS.
